(57) **CLAIM**

The ornamental design for a desk part, as shown and described.

DESCRIPTION

FIG. 1 is a top perspective view of a desk part showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof;

FIG. 8 is a right side view thereof;

FIG. 9 is a front perspective view of the desk part shown in an environment of use; and,

FIG. 10 is a front elevational view of the desk part thereof. The broken lines illustrate environment that forms no part of the claimed design.
